HEN'S NEST

Rufus V. Allen, Chino, Calif.

Application June 11, 1948, Serial No. 32,409

4 Claims. (Cl. 119—50)

1

This invention relates to new and useful improvements in nests for hens and the like, and the primary object of the present invention is to provide a nest having an entrance door, an exit door and novel and improved means operatively connecting the said doors whereby the same will be simultaneously actuated to an open or closed position.

Another important object of the present invention is to provide a hen's nest including an entrance door that is normally retained in an open position and novel and improved means exerting a door closing force upon the same that is insufficient to close the door until the weight of a hen is applied thereto, thus permitting the said entrance door to be swung into a closed position as a hen enters the nest.

A further object of the present invention is to provide a hen's nest that is so designed as to facilitate only a single hen to be disposed within the same and which includes a forward entrance door which is actuated to an open position as a hen leaves the nest through an exit door.

A still further aim of the present invention is to provide a hen's nest that is simple and practical in construction, strong and reliable in use, small and compact in structure, neat and attractive in appearance, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view of the present invention, and showing both doors thereof in an open position;

Figure 2 is a front elevational view of the present hen's nest, and showing the doors thereof in a closed position;

Figure 3 is a rear elevational view of Figure 2; and

Figure 4 is a longitudinal vertical sectional view taken substantially on the plane of section line 4—4 of Figure 3, and showing the doors thereof in an open position.

Referring now to the drawings in detail, wherein for the purpose of illustration, there is disclosed a preferred embodiment of the present invention, the numeral 10 represents the present hen's nest or housing generally, including a forward wall 12, a rear wall 14, an upper wall 16, a lower wall 18, and spaced side walls 20. The

2

forward wall 12 is provided with an entrance opening 22, and the rear wall 14 is provided with an exit opening 24.

Fixed to the forward wall 12, by any suitable means, is a transverse substantially horizontal support beam 26 that is disposed in spaced parallelism to the lower edge 28 of the opening 22. Hinged to the support beam 26, as at 30, adjacent its lower edge 32, is a forward or exit door 34 that is employed for closing the entrance opening 22.

Hinged as at 36 to the rear wall 14 of the housing 10 is a rear door or exit door 38 that is normally pivoted to a lowered position for closing the exit opening 24.

Fixed to the lower portion of the forward wall 12, is a forwardly extending support bracket 40 having an upper bearing portion 42 that will engage the door 34 to support the same in a substantially horizontal position.

Secured to the bottom wall 18 of the housing 10, is a plurality of pulleys, rollers or the like, 44 that engage a flexible element or cord 46 the ends of which are anchored to the outer faces 25 of the doors 34 and 38 through the medium of suitable brackets 48. This cord 46 also extends through a suitable aperture provided in the extended end 50 of the support 40.

Secured to the lower portion of the forward door 34, is a counterweight 52 that exerts a door closing force upon the door 34 insufficient to close the door until the weight of a hen is applied thereto and in which instance said door 34 will swing upwardly to a closed position, or a position closing the entrance opening 22 and the rear door 38 will be pivoted to a lowered and closed position.

In order to support the bottom wall 18 of the housing 10 above a ground surface or the like, there is provided a pair of legs 54 which will raise the bottom wall 18 sufficiently to permit the pulleys 44 to be applied thereto.

The rear exit door 38 is provided with a substantially V-shaped notch 56 that will accommodate the head portion of a hen for a purpose which will later be more fully apparent in the operation of the present invention.

In practical use of the present invention, the forward door 34 is initially lowered to that position shown in Figures 1 and 4 of the drawings and due to the connection of the same with the rear door 38, through the medium of cord 46, the rear door 38 will also be swung or raised to an open position.

As a hen enters the housing 10 by way of the forward door 34, which acts as a platform or stand, and steps upon the counterweight 52, the forward door 34 will be swung upwardly to a position for closing the entrance opening 22 and the rear door 38 will be moved downwardly to a position for closing the exit opening 24, thus preventing more than one hen from entering the nest at a single time. When the hen within the nest leaves or desires to leave the same, the said hen will place its head through the opening 56 and push forwardly upon the rear door 38 whereby the rear door will swing upwardly to an open position and effect a downward swinging and opening positioning of the forward door 34 to accommodate a further hen that may desire to enter the nest.

It should be noted, that the pulleys 44 are so arranged that the end portion of the cord 46 which is attached to the rear door 34 is so disposed as not to obstruct the notch or opening 56 provided in the rear door 38. This arrangement could be accomplished by swivelling the pulleys 44 to the bottom wall 18 or by providing groups of pulleys which are so arranged as to permit the said cord 46 to move forwardly and rearwardly without restriction.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A hen's nest comprising a housing having a forward entrance opening and a rear exit opening, a forward door hinged to said housing and swingable upwardly for closing said entrance opening, a rear door hinged to said housing and swingable downwardly for closing said exit opening, pulleys carried by said housing, a flexible element engaging said pulleys and connecting said doors for opening of the forward door upon opening of the rear door, and means for limiting the downward swinging movement of said forward door, said means comprising a combined support for the forward door and a guide for the flexible element.

2. A hen's nest comprising a housing having a forward entrance opening and a rear exit opening, a forward door hinged to said housing and swingable upwardly for closing said entrance opening, a rear door hinged to said housing and swingable downwardly for closing said exit opening, said rear door having an opening therein for receiving the head portion of a hen, a flexible connecting member between said doors, said forward door being actuated to a lowered and open position upon opening of said rear door by a hen pushing upon the latter, said forward door forming a standing platform leading into the housing when the same is in a lowered and open position, means carried by said forward door exerting a door closing force on said forward door insufficient to close the door until the weight of a hen is applied thereto, a support carried by said housing for supporting the forward door in its open

position, and a guide carried by said support slidably receiving said connecting member.

3. A hen's nest comprising a housing having a forward entrance opening and a rear exit opening, a forward door hinged to said housing and swingable upwardly for closing said entrance opening, a rear door hinged to said housing and swingable downwardly for closing said exit opening, said rear door having an opening therein for receiving the head portion of a hen, a flexible element connecting said doors for simultaneous opening movement thereof, said forward door being actuated to a lowered and open position upon opening of said rear door by a hen pushing upon the same, said forward door forming a standing platform leading into the housing when the same is in a lowered and open position, said forward door including a lower end portion extendable into said housing when said forward door is in an open position, a counterweight carried by the lower end of said forward door exerting a door closing force on the forward door insufficient to close the forward door until the weight of a hen is applied thereto, a support arm mounted on the housing for supporting the forward door in its open position, and a guide projecting laterally from said support arm slidably receiving said flexible element.

4. A hen's nest comprising a housing having a forward wall and a rear wall, said forward wall having an entrance opening and said rear wall having an exit opening, a substantially horizontal support beam fixed to said forward wall, said entrance opening having upper and lower horizontal edges and said beam being disposed between the upper and lower edges of said entrance opening and relatively close to the lower edge of said entrance opening, a rear door hinged to said rear wall and swingable downwardly for closing the exit opening, a substantially rectangular forward door having a lower edge, hinges carried by the forward door adjacent the lower edge thereof and secured to said beam, said forward door being swingable upwardly for closing the entrance opening, a counterweight carried by the forward door adjacent the lower edge thereof exerting a door closing force on said forward door insufficient to close the forward door until the weight of a hen is applied thereto, guide rollers carried by and depending from said housing, an elongated flexible element engaging said guide rollers and having upwardly extending end portions secured to said forward door and said rear door for opening of the forward door upon opening of the rear door, said rear door having a central opening, one end of said flexible element being secured to the rear door adjacent said central opening, a support arm secured to said forward wall for supporting the forward door in its open position, and a laterally projecting eye carried by said arm slidably receiving said flexible element.
